UNITED STATES PATENT OFFICE.

FRANCIS CLAUDE BLAKE, OF LONDON, ENGLAND.

CARBURETER.

SPECIFICATION forming part of Letters Patent No. 705,314, dated July 22, 1902.

Application filed November 5, 1901. Serial No. 81,270. (No model.)

To all whom it may concern:

Be it known that I, FRANCIS CLAUDE BLAKE, engineer, a subject of the King of Great Britain, residing at Motor Works, Station avenue, Kew Gardens, London, England, have invented a certain new and useful Improvement in carbureters, of which the following is a full, clear, and exact description, and for which I have applied for Letters Patent in Great Britain, dated April 15, 1901; in Germany, dated May 3, 1901; in France, dated August 20, 1901, and in Belgium, dated August 20, 1901.

his invention relates to carbureting apparatus for explosion-engines, and in particular improved means for feeding the petrol or other hydrocarbon to the motor of a motor-car. This petrol-feed device has a double action and possesses advantages over the ordinary float feed or similar devices for this purpose.

The invention consists of a petrol-chamber forming, preferably, the base of the vacuum-chamber of the carbureter and having a flexible diaphragm to which is secured a nozzle or spout, with a ball-valve or other means for cutting off the petrol from the spout, the intermittent fed of petrol from within the petrol-chamber and through the spout being consequent upon, first, the action of the vacuum on the flexible diaphragm, and, secondly, the return or rebound of the diaphragm. The petrol-chamber is constantly supplied from a petrol-reservoir by either pressure or gravity, and the vacuum acting upon the flexible diaphragm of the chamber is caused by the aspiration of the motor in taking in its charge. The feed is regulated by adjusting the amount of lift of the diaphragm. The diaphragm is made of any suitable flexible material sufficiently springy and not acted upon by the petrol, and one or more air-inlets of any adjustable pattern are provided for the carbureter to adjust the mixture and regulate the degree of vacuum.

Upon the accompanying drawings, Figure 1 is a sectional elevation of one form of the invention. Fig. 2 represents a detail modification in the same. Fig. 3 is a sectional elevation of a modified form of carbureter, and Fig. 4 is a plan view (seen from underneath) of the base of the jet.

Referring to Fig. 1, the vacuum-chamber *a*

is preferably dome-shaped and the petrol-chamber *b* is of circular or other shape secured to its bottom, the flexible diaphragm or cap *c* of the petrol-chamber forming the base of the vacuum-chamber. Preferably the base and walls of the petrol-chamber are rigid, while the flexible diaphragm *c* is of concentrically-corrugated sheet metal, such as German silver, nickel, or copper. Ordinary air-inlets, consisting of perforated disks arranged to "hit or miss" corresponding holes in the chamber *a*, are shown at *d* and *e*. A branch pipe *f* delivers to the motor, and a casing *g* may depend from the branch pipe to within the chamber *a*.

To the center of the flexible diaphragm *c* of the petrol-chamber *b* is integrally secured a nozzle or spout *h*, projecting to about the center of the height of chamber *a* and shielded, preferably, by the dependent casing *g*. This spout or jet has a very fine bore, and the portion of the spout within the petrol-chamber forms a seat for a ball *i*, arranged to close the lower bore of the spout. Ball *i* is supported upon an adjustable rod *k* within a cup *l*. This cup is of such internal diameter that the ball *i* can rest only upon the rod *k*. The latter can be adjusted from outside the device, so that by turning the rod the position of the ball *i* can be slightly raised or lowered.

The petrol is fed in any suitable manner from the reservoir to the petrol-chamber *b*, and it may conveniently be admitted at inlet *m*. It may be necessary to readjust the rod *k* when filling up the petrol-reservoir to avoid flooding the chamber *a*, since the pressure of the full head of petrol may tend to lift the diaphragm slightly. A small quantity of air or vapor may be allowed to remain in the petrol-chamber, and a cage may be provided additionally around the ball *i* or its cup *l* to prevent the ball getting out of position. A shield *n*, of conical shape, may be arranged as shown to prevent the petrol from being thrown out through *d* and also to break up the petrol pumped in by the reflex action of the diaphragm.

The position of the petrol injected into the chamber *a* by the reaction of the diaphragm is immaterial, since it is drawn out of the chamber *a* to the explosion-chamber by the next suction-stroke of the piston. The petrol,

in fact, may be directly projected upon the cone *n*, or it may be sprayed upon the casing *g*, or, again, it may rest upon the top of the diaphragm *c* until the next suction-stroke of the engine.

Instead of the ball *i* a hollow conical valve, Fig. 2, of an arrow-head shape may be seated loosely and balanced upon the top of rod *k*, its point closing the lower entrance to spout *h* and otherwise acting as the ball in Fig. 1.

Any ordinary and suitable non-return valve may be arranged within the petrol-supply pipe, acting in conjunction with the pumping action of the diaphragm.

When the motor sucks from the vacuum-chamber *a*, the spout *h* and flexible diaphragm *c* are drawn inwardly, the seat thus rising from the ball *i*, and petrol in the form of spray is drawn into the casing *g*, where it meets the incoming air, and these pass to the motor together. The jet of petrol so withdrawn is replaced from the reservoir-supply, and when the suction ceases the flexible plate *c* subsides by its own elasticity, and a further quantity of petrol is forced or pumped up through the spout, leaving a partial charge ready for the next aspiration or stroke of the piston.

The modification shown in Fig. 3 has been designed to dispense with a non-return valve between petrol inlet and tank to avoid having to readjust the valve when refilling the tank and to avoid all possible flooding. The valve here consists of a plug in the shape of a peg-top or spinning-top *o*, mounted upon a spiral spring *p* and centered in the jet *h* and adjustable rod *k*, which latter is made hollow. The lower part of the seat of jet *h* is provided with a number of grooves or slots *h'*, (see Fig. 4,) or, alternatively, radial flats may be formed upon the top of the conical surface *o*, the object in either case being to allow access of petrol to the spout at all times. The lower part of the top-shaped valve *o* can close or block the hollowed part of rod *k*. The rod *k* at its lower part is provided with a number of ports through which petrol may be admitted from the inlet-pipe *m*. This latter, it will be noticed, does not now deliver directly into the chamber *b*. The remaining construction is clearly shown on the drawings. *r* is a gland-nut, *s* packing within the same, and *t* the wheel for regulating the valve. The action of this form of valve *o* is similar to the previous; but when the diaphragm *c* rises the top-shaped valve *o* is raised by means of the spring *p*. Petrol is now sucked out through jet *h* into *a*, as before, and fresh petrol is also supplied to the chamber *b* through *k*. When this stroke of the piston has ceased, the dia-

phragm *c* subsides and tube *k* is blocked by the base of the top-shaped valve *o*, the reflex action of the diaphragm pumping up a further supply of petrol, as explained above.

It is to be noted in both forms of the carbureter that from the diaphragm downward the lower part of the device is made in one piece. Thus a new base to chamber *a* can be screwed into position without trouble should this ever become necessary.

Where heavy hydrocarbons are used, it may be necessary to add to the device one of the ordinary chambers or arrangements whereon such hydrocarbon is vaporized by means of the heat from the exhaust or otherwise.

Having thus described my invention, wh^{ch} I claim as such, and desire to secure by Letters Patent, is—

1. A double-acting feed device for use in trol-engines comprising a flexible diaphragm forming the bottom of the suction-chamber and having a spout, petrol being intermittently fed into the suction-chamber first by the lift of the diaphragm and by reason of the suction action of the piston, and secondly by the return of the diaphragm to its original position as the suction action ceases.

2. A petrol-feed device, consisting of a flexible diaphragm forming the base of a suction-chamber and the cover for a petrol-chamber, said diaphragm having a spout delivering from the petrol-chamber into the suction-chamber, a valve located within said petrol-chamber and arranged to close said spout from underneath, said valve being mounted upon a screwed rod and adjustable from the exterior of the device, and said petrol-chamber being supplied from the petrol-tank.

3. In a petrol-feed device having a flexible diaphragm fitted with a jet, a hollow conical plug balanced loosely upon a rod adjustable from the exterior of the apparatus and arranged to close the jet.

4. A petrol-feed device, comprising a flexible diaphragm forming a cover for a petrol-chamber and fitted with a spout, a plug or valve arranged to be guided by entering the said spout from underneath and to close an adjustable hollowed rod communicating with the petrol-inlet, said plug allowing at all times access from the petrol-chamber to the jet and being mounted upon a spring within the petrol-chamber, and arranged to follow the rise and fall of the jet.

In witness whereof I have hereunto set my hand in presence of two witnesses.

FRANCIS CLAYDE BLAKE.
